TRAVELING-WAVE TUBE

Horace R. Johnson, Venice, and Dean A. Watkins, Menlo Park, Calif., assignors, by mesne assignments, to Hughes Aircraft Company, a corporation of Delaware

Application December 30, 1953, Serial No. 401,303

7 Claims. (Cl. 315—3.6)

The present invention relates to traveling-wave tubes and more particularly to an electron stream amplifier tube incorporating a helix with an enlarged opening for accommodating a larger stream current and having a stop band for suppressing backward wave oscillations in selected modes.

As is commonly known, conventional traveling-wave tubes have found widespread use as microwave amplifiers because of their ability to provide gain over a broad bandwidth. Present day traveling-wave tubes generally comprise a helical structure capable of propagating an electromagnetic signal wave at a velocity considerably less than the velocity of light. The free-space wavelength reduced by a factor equal to the ratio of this velocity to the velocity of light is known as the guide wavelength. In their operation, an electron stream is directed through the helical structure propagating the wave at an appropriate velocity so as to interact constructively with the wave. In order for the wave propagated by the helix to interact efficiently with the electron stream, it is necessary for the axial components of the electric field of the wave to exist in the region of electron flow. To accomplish this, the general procedure is to use a helix having a circumference less than two guide wavelengths at the signal frequency so that the electric field of the wave has axial components across the entire opening of the helix. When this is done, all of the cross sectional area of an electron stream directed through the helix is in the electric field of the wave, thus effecting efficient interaction between the electron stream and the wave.

Traveling-wave tubes of this type have certain obvious limitations. As an example, it is apparent that as higher and higher frequencies are amplified, the necessary opening in the helix to effect optimum interaction between the wave and the electron stream becomes increasingly smaller. The smaller opening in the helix of conventional tubes designed to operate at higher frequencies reduces the stream current that may be accommodated, thereby reducing the available power output.

The aforementioned limitation is circumvented in the tube of the present invention by employing a helix having a considerably enlarged opening. This, however, introduces other basic problems, as will be explained, which heretofore have never been solved. As is commonly known, a helix may propagate a backward wave as well as the fundamental forward wave. A backward wave is a wave which has phase and group velocities traveling in opposite directions as distinguished from the fundamental wave which has phase and group velocities traveling in the same direction. As previously stated, when the helix has a circumference of less than two guide wavelengths of the propagated wave, axial components of the electric field of the fundamental wave exist across the entire opening of the helix. The axial component of the electric field of the backward wave space harmonic, however, is very small and exists only in the regions contiguous to the wires of the helix. Hence, under normal circumstances, the backward wave may generally be neglected.

When the opening in the helix is made larger while maintaining a fixed pitch angle, the axial electric fields of both the fundamental and backward waves are of substantially the same magnitude and exist, for the most part, in the regions adjacent to the wires of the helix. Hence, when a helix having an enlarged opening is used, only the flow of stream electrons in the regions adjacent to the wires of the helix may constructively interact with one of the electric fields of the waves propagated by the helix. This, however, creates the basic problem of having the electron stream flow in regions where the electric fields of the fundamental and backward waves are of the same order of magnitude. Under normal circumstances, this condition would result in the start of backward wave oscillations when any substantial amount of current is made to flow in the electron stream. For a tube operating as a forward wave amplifier, however, it is necessary to prevent these backward wave oscillations. For a traveling-wave tube amplifier having a helix of typical pitch angle and operating in the region where its helix is non-dispersive, it has been found that the frequency of a backward wave propagated by the helix is such that its circumference is either approximately one-half wavelength of the wave or approximately one wavelength corresponding to what may be called the low and the high frequency backward wave modes of propagation on the helix. In addition, for a predetermined electron stream velocity, oscillations will normally occur within a very narrow band of frequencies for the low frequency backward waves because of the greater gain in this mode.

As is well known, a helix with a typical pitch angle that is large compared to the free space wavelength of a propagated wave is non-dispersive. Thus, when a helix of this type is used in a traveling-wave tube operating as a forward wave amplifier, the electron stream will be at a substantially constant velocity for frequencies over its entire range of operation. Therefore, it is evident that means for attenuating the frequencies at which backward wave oscillations occur for an electron stream velocity corresponding to the forward wave mode of operation may be provided by an appropriate stop band.

This stop band may be provided, for example, by disposing periodic discontinuities along the turns of the helix separated by a multiple of one-half free space wavelength for the frequency to be attenuated. In the event that it is desired to attenuate a broader band of frequencies, it is only necessary to increase the length of such discontinuity along the periphery of the helix. These discontinuities, because of their periodicity and proximity to the helix, will form either a spiral or a line along the helix; hence they may be provided by a single rod or other elongated member. In order to prevent additional extraneous modes of propagation through the helix, the rod is preferably made with its conductivity in the longitudinal direction interrupted at intervals of less than the pitch of the helix.

One embodiment of the tube of the present invention comprises an enlarged helix having a circumference of the order of 0.6 of a free space wavelength of the signal to be amplified and a stop band to prevent backward wave oscillations. In its operation, a hollow cylindrical electron stream, having a diameter slightly less than the inner diameter of the helix, is directed concentrically through the helix to effect amplification of the signal. Because of the greater cross sectional area available for the electron stream, it is seen that the helix incorporated in this tube has an opening that may accommodate considerably larger stream currents than those normally used. Assuming an upper limit of beam current density, this larger stream current enables the traveling-wave tube of the present invention to provide a power output that is con-

siderably greater than that available from conventional traveling-wave tubes.

In addition, the tube disclosed here has a basic fundamental advantage in that the larger sized helix enables signals of higher frequencies to be amplified. A concomitant structural advantage is, of course, that for a given frequency, a larger helix may be utilized.

A further advantage of the disclosed device is that the circumference of the helix and the beam voltage of the traveling-wave tube may be chosen so as to provide a predetermined power output within a desired frequency range. As is generally known, optimum gain occurs at a frequency where the difference between the circumference of the helix and the circumference of the electron stream is of the order of from 1.8 to 2.0 guide wavelengths. Thus, the circumference of the electron stream may be chosen so that the frequency at which optimum gain occurs coincides with the mean frequency of the operating frequency range.

In a traveling-wave tube having a solid electron stream, on the other hand, one must choose a helix having a circumference less than 0.2 of a free space wavelength at the operating frequency in order to avoid backward wave oscillations. In order to obtain a desired power output, it is necessary for the beam voltage to be in excess of a certain predetermined value in that the beam current is limited by its perveance. The choice of these parameters in a solid stream tube, however, also determines the frequency at which optimum gain occurs. In the case of traveling-wave tubes designed for substantially large power outputs, this frequency is substantially higher than the operating frequency. This results in the tube having high gain in a frequency range for which there would generally be a poor impedance match at its output, thus destroying the utility of the tube by making it have a tendency to commence into uncontrolled oscillations at frequencies within this range.

A particular application of the tube of the present invention is that the tube may be made to oscillate on the high frequency backward wave modes by the use of an appropriate stop band to attenuate the low frequency backward waves. When operating in this manner, the tube described here may be used to generate higher frequencies than heretofore possible with conventional helical-type traveling-wave tubes.

An additional application of the tube of the present invention is that it is adaptable to operation as a voltage tuned amplifier through a frequency range substantially greater than 3000 megacycles. Heretofore, traveling-wave type voltage tuned amplifiers have been made by operating a conventional traveling-wave tube in the dispersive range of its helix operating on its fundamental forward wave mode. At a frequency of 3000 megacycles, a helix having an extremely small circumference was required, and at higher frequencies it was found to be entirely impractical to make a voltage tuned amplifier of this type. The traveling-wave tube of the present invention, on the other hand, may be operated so as to amplify by means of interaction of the electron stream with a highly dispersive component of a new mode of propagation covering a frequency range substantially higher than heretofore possible by merely increasing the electron stream velocity. Inasmuch as dispersion is the rate of change of the phase velocity of a wave with respect to frequency, the tube of the present invention may be tuned through the band of frequencies corresponding to the portion of the frequency spectrum where the aforementioned component is highly dispersive by merely varying the velocity of the electron stream through a range that is coextensive with the range covered by the phase velocity of the wave.

Additional embodiments of the tube of the present invention may incorporate a multifilar helix for providing an even larger opening than in the aforementioned embodiment. A traveling-wave tube having an enlarged bi-

filar helix is shown and described as an example of this type of tube.

It is therefore an object of this invention to provide an improved stream-type amplifier tube.

Another object of this invention is to provide an electron stream-type tube incorporating an enlarged helical structure capable of accommodating greater stream currents and thus produce more power output than heretofore possible with traveling-wave tubes employing helices of conventional size.

Still another object of this invention is to provide an electron stream-type amplifier tube including a helical wave propagating structure of relatively large dimensions as compared to the free space operating wavelength.

A further object of this invention is to provide an electron stream-type amplifier tube incorporating an enlarged N-filar helical wave propagating structure having stop bands for suppressing backward wave oscillations in selected modes.

20 A still further object of this invention is to provide a microwave oscillator by employing a stream-amplifier tube incorporating an N-filar helix with appropriate stop bands to enable it to oscillate on the higher order backward wave mode.

25 An additional object of this invention is to provide a stream-type amplifier tube incorporating an N-filar helix of appropriate pitch and diameter for adapting it to operate as a voltage-tuned amplifier for frequencies as high as 12,000 megacycles.

30 The novel features which are believed to be characteristic of the invention, both as to its organization and method of operation, together with further objects and advantages thereof, will be better understood from the following description considered in connection with the 35 accompanying drawings, in which several embodiments of the invention are illustrated by way of examples. It is to be expressly understood, however, that the drawings are for the purpose of illustration and description only, and are not intended as a definition of the limits of the 40 invention.

Figs. 1 and 7 are diagrammatic sectional views of two 45 embodiments of the invention together with associated circuitry;

Figs. 2, 3 and 9 are alternate forms of the apparatus for providing the stop band in the tubes of Figs. 1 and 7;

45 Figs. 4 and 6 show preferred locations of stop bands and operating ranges on plots of the phase velocity of a wave propagated on a helix versus the ratio of the circumference of the helix to the wavelength at the frequency of operation;

50 Fig. 5 is a plot of gain and power output versus electron stream current for a typical electron stream amplifier tube; and

Fig. 8 is a cross sectional view of the tube of Fig. 7.

55 Referring now to Fig. 1, there is shown a diagrammatic sectional view of an electron stream-type amplifier tube of the present invention. An envelope 10, which provides the necessary evacuated chamber, consists of a long cylindrical structure having an enlarged portion at the left extremity, as viewed in the figure. Within the enlarged portion of envelope 10, there is disposed an electron gun 12 for producing a hollow cylindrical electron stream. Electron gun 12 comprises an annular cathode 14 with a heater 16, a focusing electrode 18, and an accelerating electrode 20, the electrodes 18 and 22 being provided with conformal apertures to allow passage therethrough of the electron stream.

60 Cathode 14 is disposed in a plane normal to the longitudinal axis of envelope 10. Heater 16 of cathode 14 is connected across a source of potential, such as a battery 22, one terminal of which is connected to cathode 14, as shown. The electrode 18, disposed adjacent to and to the right of the cathode 14, as shown in the figure, has an inner and an outer surface of revolution at an acute angle about the longitudinal axis of envelope 10 to provide

focusing for the electron stream. Cathode 14 and focusing electrode 18 are connected together and are, in turn, connected to the negative terminal of a source of potential such as a battery 24, the positive terminal of which is connected to ground. The potential provided by battery 24 may be of the order of -1500 volts with respect to ground.

Accelerating electrode 20 is disposed in a plane normal to the longitudinal axis of envelope 10 and to the right of focusing electrode 18 as viewed in the drawing. Electrode 20 is maintained at a potential that is positive with respect to the potential of cathode 14 by means of a connection to a battery 26 connected from electrode 20 to ground. This potential may be of the order of 300 volts positive with respect to ground.

A solenoid 28 is positioned symmetrically about the complete length of envelope 10. An appropriate direct current is made to flow through solenoid 28 by means of a battery 30 so as to produce a magnetic field, which may be of the order of 600 gauss, extending axially along the tube. The purpose of this magnetic field is to keep the electron stream constrained throughout the active length of the tube.

Positioned concentrically about the electron stream in the direction of the electron flow is a tape helix 32 which has a circumference of the order of one-half wavelength at the operating frequency. In general, the inner diameter of the hollow electron stream should be at least 0.70 the inner diameter of helix 32 in order that the helix present a high impedance to the electron stream. A material such as tungsten or molybdenum is suitable for making the helix, the main prerequisites being that it maintain its form, especially with respect to its pitch and diameter, and that it be a good electrical conductor. Positioned about the outer periphery of helix 32 is a thin glass sheath 34, the purpose of the glass sheath 34 being to support the helix 32 throughout its length so that it retains its form.

A discontinuity is provided on each turn of helix 32 by means of a spiral dielectric rod 36 having small isolated areas 37 or 38 of conductive material disposed over the greater portion of its surface, as illustrated in Figs. 2 and 3. Rod 36 is inserted between glass sheath 34 and envelope 10 to hold helix 32 in a concentric position about the electron stream. Alternate forms of member 36 are shown in Figs. 2 and 3. Referring to Fig. 2, there is illustrated a short section of the dielectric rod 36. Conductivity in the transverse direction is provided on this rod by closely spaced, narrow metal bands 37, the approximate space between bands being 0.1 the width of a band which is preferably less than the pitch of helix 32. A rod of this type may be made, for example, by first plating a dielectric rod with a metal, and then removing the metal at periodic intervals along the rod by means of an etching process. A short section of an alternate form of rod 36 is shown in Fig. 3. This figure shows a multitude of small isolated reflecting elements 38 deposited on the surface of a dielectric rod. A rod of this type may be made, for example, by attaching flakes of conductive material such as, for example, aluminum to the rod with a suitable binder.

Referring again to Fig. 1, a conductive coating 39 is deposited on the inside of glass envelope 10 which extends from accelerating electrode 20 to the beginning of helix 32. This conductive coating 39 provides a drift space for the electron stream in this region and is maintained at ground potential by means of a connection thereto.

An input to the extremity of tape helix 32 nearest electron gun 12 is provided by a section of coaxial cable 40. A center conductor 41 of the coaxial cable 40 connects from the input terminal through the envelope 10 to the first turn of helix 32. The outer conductor of cable 40 is connected to a ferrule 42 which is disposed concentrically about the first several turns of helix 32 on the outside of envelope 10. The extremity of ferrule 42 farthest away

from electron gun 12 is flared out in order to improve the impedance match between coaxial cable 40 and helix 32. The outer conductor of cable 40 together with ferrule 42 may be maintained at any substantially fixed potential such as, for example, at ground by means of a connection thereto.

An output is provided from helix 32 at the farthest extremity from electron gun 12 by a section of coaxial cable 45. A center conductor 46 of cable 45 connects from the last turn of helix 32 through envelope 10 to an output terminal 47. The outer conductor of cable 45 connects to a ferrule 49 which is disposed concentrically about the last few turns of helix 32 on the outside of envelope 10. As before, the impedance match between helix 32 and coaxial cable 45 is improved by flaring out the extremity of ferrule 49 nearest the electron gun 12. The outer conductor of cable 45, together with ferrule 49, are maintained at ground potential by means of a suitable connection thereto. Helix 32 is also operated at ground potential by means of a connection from output terminal 47 through an isolation resistor 51 to ground.

Disposed so as to intercept the electron stream after it has progressed through the helix 32, is a collector electrode 53. Electrode 53 is maintained at a potential that is several hundred volts negative with respect to the potential of helix 32 in order that maximum energy may be extracted from the stream electrons. Accordingly, a potential of the order of -300 with respect to ground is applied to electrode 53 by means of a connection through envelope 10 to the negative terminal of a battery 55, the positive terminal of which is connected to ground.

In the operation of the traveling-wave tube of the present invention, a signal to be amplified is first applied to the input terminal. This signal is, in turn, impressed on the first turn of helix 32 through coaxial cable 40. The comparatively large circumference of the helix employed relative to the free space wavelength of the signal at the operating frequency enables an impedance match to be obtained between conventional coaxial cable and the helix.

The signal is propagated along the helix 32 as an electromagnetic wave having a velocity that is slightly less than the velocity of the electron stream so as to effect a transfer of energy from the stream to the wave. Inasmuch as the axial components of the wave are, for the most part, in the region contiguous to the periphery of the helix 32, it is necessary to restrict the flow of stream electrons to this region. Hence, a hollow cylindrical electron stream is employed to effect efficient interaction with the electric field of the traveling wave.

The electric fields of the backward wave modes of propagation, however, also exist in the region contiguous to the periphery of the helix 32. Since these backward waves are inherently regenerative in character, it is necessary to provide stop bands to prevent backward wave oscillations that would result from the above structure. The relationship between these backward wave modes and the fundamental forward wave mode of propagation on the helix is shown in Fig. 4. Referring to this figure, there is plotted the phase velocity of the waves as a fraction of the velocity of light versus the helix circumference in free space wavelengths at the signal frequency, the latter generally being designated as "ka." In this figure, line 60 represents the fundamental forward wave mode, and lines 62, 64 represent the low and high frequency backward wave modes, respectively. The tube of the present invention, when employed as an amplifier, operates in the region where the helix 32 is non-dispersive. This region is indicated by portion 61 of the line 60 representing the fundamental forward wave mode. Because of the non-dispersive characteristic of the helix 32 throughout this portion 61, the phase velocity, v_p , of

the wave remains substantially constant, thus requiring a substantially constant electron stream velocity. It is possible, however, for the tube to commence backward wave oscillations at the points 68, 69 where this electron stream velocity is common with the phase velocity of the backward wave modes of propagation.

Therefore, in order to prevent backward oscillations, stop bands are provided for the portions 71, 72 between ka_1 , ka_2 and $2ka_1$, $2ka_2$, respectively, of the lines 62, 64 representing the backward waves on the helix 32. The limits of portions 71, 72 will be apparent from the nature and characteristics of the type of stop band used.

As previously mentioned, one form of stop band may be provided by disposing discontinuities at periodic intervals along the turns of the helix. When the interval between subsequent discontinuities is one-half wavelength or multiple thereof, a stop band is formed for the corresponding frequencies. The reason for this is because the reflected portion of the wave has progressed through a complete cycle plus an additional 180° upon being reflected, and thus tends to cancel unreflected portions of the wave. The width of the stop band may be broadened by extending the discontinuities about the periphery of the helix. A stop band of this type has the characteristic of being recurrent at double the frequency of the fundamental stop band.

In the present instance, it is desired to provide stop bands for the backward waves having phase velocities in the interval between the dashed lines 74 of Fig. 4 in order to prevent backward wave oscillations when amplifying signals in the non-dispersive portion 61 of line 60. It is seen from the drawing that in order to include the desired interval about v_p' , it is necessary to extend the stop band to include the portions 71, 72 on the lines 62, 64, respectively, representing the backward wave modes.

In the tube described here, it is necessary to locate the stop bands to attenuate frequencies corresponding to wavelengths that are slightly less than the circumference of the helix in the high frequency backward wave mode, and slightly less than twice the circumference of the helix in the low frequency backward wave mode. It is therefore necessary for the helical spiral rod 36 to extend between points on the helix 32 that are slightly greater than a complete turn apart. Hence, in the present case, the spiral rod 36 and helix 32 rotate in the same direction in proceeding along the length of the tube.

The tube of the present invention may thus be utilized to amplify signals of frequencies within the non-dispersive band of the helix that are not included within the stop band. The signal is propagated along the helix 32 as a growing wave which continuously interacts with the electron stream. At the extremity of helix 32 farthest from electron gun 12, the amplified wave is impressed on coaxial cable 45 to provide an amplified output signal at output terminal 47. Collector electrode 53 is maintained negative relative to the potential of helix 32 so as to effect maximum transfer of the signal energy propagated by the electron stream to the electromagnetic wave on the helix prior to dissipation of all the energy of the electron stream at the collector.

An illustration of the substantial increase in the power output available from a tube of the present invention incorporating a stop band of the type described, to prevent backward wave oscillations, is illustrated in Fig. 5 which shows gain and power output versus beam current represented by lines 80, 82, respectively. It is seen that the gain in decibels increases rapidly in the region where the beam current is small and less rapidly for the larger values of beam current. The power output, on the other hand, increases approximately as the three-halves power of beam current. Thus it is apparent that the stop bands, by preventing the propagation of waves at which backward wave oscillations occur, allow greater current to flow without

backward wave oscillations commencing, and therefore greatly increase the power output available from the tube.

As previously stated, it is considered that the use of stop bands to cause the tubes of the present invention to operate as backward wave oscillators on the high frequency backward wave mode of propagation on the helix, is within the teachings of this invention. An illustration of the manner in which this may be accomplished is shown in Fig. 6. Referring to Fig. 6, there is shown a plot of the phase velocity of an electromagnetic wave versus the ratio of the circumference of the helix to the free space wavelength at the frequency of the wave for the fundamental forward wave and backward wave modes propagation represented by lines 60, 62 and 64 in the same manner as in Fig. 4.

Under normal circumstances, the impedance of the helix for the backward wave mode represented by line 62 is greater than its impedance for the mode represented by line 64. Hence, when possible, backward wave oscillations will be on the low frequency mode represented by line 62. As seen in Fig. 6, the high frequency backward wave mode represented by line 64 commences at a phase velocity of v_p'' . In order to prevent oscillations on the low frequency backward wave mode for phase velocities higher than v_p'' , it is necessary to employ a stop band to attenuate frequencies in the interval from ka_3 to ka_4 represented by a portion 90 of the line 62.

A stop band of the type described, however, will also attenuate frequencies in the region in excess of $2ka_3$ represented by a portion 92 of the line 64. Thus, as can be seen from the figure, the tube of the present invention may oscillate along the lower portion, as indicated, of the high frequency backward wave mode represented by line 64. In this manner, extremely high frequencies may be generated by the tubes of the present invention. The output from the tube, in this case, appears at the input terminal.

Further, as previously set forth, it is considered that the operation of the tubes of the disclosed invention as voltage tuned amplifiers is within the scope of the teachings of the present specification. This mode of operation is accomplished by simply increasing the velocity of the electron stream so as to effect the amplification of a highly dispersive component of the forward wave mode rather than the fundamental component. The characteristics of this dispersive component of the forward wave mode are described in a doctoral thesis entitled, "Electromagnetic Wave Propagation on Helical Conductors," by Samuel Sensiper which was published by the Research Laboratory of Electronics, Massachusetts Institute of Technology on May 16, 1951, in Cambridge, Massachusetts, as Technical Report No. 194. In this report, the aforementioned highly dispersive component is referred to as the -1 component of the ht_1' mode. A plot of the phase velocity of this component versus the ka of the helix appears on page 69 in Fig. 30(b) of the report. The disclosed tubes are operated on the -1 component of the ht_1' mode by merely increasing the velocity of the electron stream so that it is substantially equal to this phase velocity. The velocity of the electron stream may be increased by merely increasing the voltage provided by potential source 24 which is impressed on cathode 14 of electron gun 12 in the tube of Fig. 1. A stop band is necessary to prevent backward wave oscillations from commencing as in the previous cases.

It is also apparent, in operating on the -1 component of the ht_1' mode, that gain is also provided at the low frequency end of the conventional forward wave mode which is designated as the fundamental component of the ht_0 mode in the aforementioned report. Since the output circuit is not designed to provide an impedance match for such low frequencies, there is a good possibility of reflections at the output being of sufficient magnitude to cause oscillations to commence. The electric fields of an electromagnetic wave corresponding to these low fre-

quencies propagated on the helix extends radially outwards therefrom for several diameters of the helix. Thus, oscillations in the conventional forward wave mode may be prevented by disposing a lossy coating concentrically about the helix and spaced several diameters therefrom so as to reduce the loop gain in this mode to less than unity. Inasmuch as the electric fields for the highly dispersive -1 component of the h_{11}' mode are very close to the wires of the helix, propagation of this mode is not affected by the lossy coating.

In designating the helix of a traveling-wave tube for operation as a voltage tuned amplifier employing the -1 component of the h_{11}' mode of propagation, the restriction placed on the pitch angle, ψ , of the helix is that it should satisfy the relation

$$\frac{\sqrt{V_0}}{505} \approx \frac{ka \tan \psi}{ka - 1} = \frac{2\pi f_0 a \tan \psi}{2\pi f_0 a - c}$$

wherein

V_0 is the voltage through which the stream electrons are accelerated,

ka is the circumference of the helix in free space wavelengths,

a is the radius of the helix,

c is the velocity of light, and

f_0 is the mean frequency of the band of frequencies amplified.

The above relation is approximate in that the assumption is made that the velocity of the electron stream may be substituted for the phase velocity of the wave. Further, the relation is only valid for ka greater than 1.0 and V_0 less than 20,000 volts.

In addition to the above, it is also considered that the use of multi-filar helix, as the wave-propagating structure in the tube described here, is also within the scope of the teachings of the present specification. As an example of an embodiment of this type, a tube incorporating a parallel fed bifilar helix is shown and described. The use of a parallel fed bifilar helix enables the same phase relations to be maintained about its periphery as for unifilar helix of only half the circumference. Hence, the employment of a bifilar helix makes it possible to use larger beam currents and thus increase the power output of the tube or, alternatively, to construct a tube for amplifying signals of higher frequency.

Referring to Fig. 7, there is shown an embodiment of the tube of the present invention incorporating a bifilar helix. The envelope 10, electron gun 12, solenoid 28, conductive coating 39, and collector electrode 53, together with associated circuitry of this tube, are the same as for the corresponding elements described in connection with the tube of Fig. 1. A bifilar helix 100 is disposed concentrically about the path of the electron stream and extends approximately from the termination of conductive coating 39 to the collector electrode 53. A thin glass sheath 102 is disposed concentrically about helix 100 in order that it retain its form. Helix 100 is held in a position concentric about the path of the electron stream by means of two dielectric rods 104, 105 and a transversely conducting elongated member 106 (see Fig. 8). Rods 104, 105 and member 106 are angularly spaced at approximately 120° from each other so as to hold the helix 100 rigidly in place. The angular spacing is not critical and may be varied with the width of member 106. A cross sectional view of the tube taken at section 3-3' showing this arrangement is illustrated in Fig. 8.

Elongated member 106, in addition to holding the helix 100 in place, provides a stop band. Member 106 has a kidney-shaped cross section, as shown in Figs. 8 and 9, so as to extend partly around the periphery of the helix and thus increase the width of the stop band. Member 106 may comprise, for example, a dielectric rod 107 of appropriate cross section, having a series of metal bands 103 disposed along its entire length. An enlarged view of

member 106, showing this construction, is illustrated in Fig. 9.

Referring again to Fig. 7, means for providing a parallel feed from input terminal 110 to bifilar helix 100 is provided by equal lengths of coaxial cable 112, 114 connecting the extremities of the two helices nearest electron gun 12 forming bifilar helix 100 to a common junction 116 which in turn is connected to input terminal 110. A ferrule 118 is disposed about the first few turns of helix 100 outside of envelope 10 and flared out at the extremity farthest from electron gun 12 in the same manner as before, to improve the impedance match between the coaxial cables 112, 114 and helix 100. The outer conductors of cables 112, 114 and ferrule 118 are maintained at ground potential by a connection thereto.

An output circuit for the tube is provided by equal lengths of coaxial cable 119, 120 connected from the two extremities of the helices of bifilar helix 100 farthest from electron gun 12 to a common junction 122 which is, in turn, connected to an output terminal 124. A matching ferrule 125 is disposed about the last few turns of helix 100 on the outside of envelope 10 and connected to the outer conductors of coaxial cables 119, 120. These outer conductors and ferrule 125 are maintained at ground potential by a connection thereto. Helix 100 is also maintained at ground potential by means of a connection from output terminal 124 through an isolation resistor 126 to ground.

The operation of the tube of the present invention incorporating a bifilar helix is essentially the same as for the previously described tube employing a unifilar helix. It is to be noted, however, that in the present case, modes of propagation comparable with those of a unifilar helix are attained by making the circumference of the bifilar helix twice that of the unifilar helix. Thus, the tube incorporating the bifilar helix illustrated in Fig. 7 may be adapted to operate either as a high power traveling-wave amplifier tube, a backward wave oscillator, or a voltage-tuned oscillator in the same manner as the tube illustrated in Fig. 1. Further, it is also apparent that it is within the teachings of the present specification that the disclosed techniques may be employed so as to operate any traveling-wave tube incorporating an N-filar helix in the aforementioned modes.

What is claimed as new is:

1. A traveling wave tube comprising an N-filar conductive helix capable of propagating a wave having a phase velocity substantially less than the velocity of light, where N is an integer equal to or greater than one, and the circumference per turn of said helix is greater than $0.2N$ free space wavelength of said wave; means for producing an electron stream; means for directing said electron stream along a path parallel to the longitudinal axis of and contiguous to said helix to increase the amplitude of said wave; an elongated dielectric member disposed along and immediately adjacent periodically spaced points on successive turns of said helix, said elongated dielectric member having a pitch substantially greater than the pitch of said helix and a plurality of relatively small isolated areas of conductive material disposed on said elongated dielectric member to provide electrical reflectors whereby an electromagnetic wave being propagated around the turns of said helix is partially reflected at periodically spaced points therealong thereby to attenuate waves within a predetermined band of frequencies capable of being propagated by said helix including the frequency at which oscillations on the low frequency backward wave mode would occur.

2. The traveling wave tube as claimed in claim 1 where-in the width of said elongated member is increased where-by said member extends about a larger portion of the periphery of said helix thereby to increase the width of said predetermined band of frequencies.

3. The traveling wave tube as claimed in claim 1, where-in said elongated dielectric member comprises a rod hav-

ing a series of narrow conductive bands disposed successively along its entire length, the width of said bands being less than the distance between successive turns of said N-filar conductive helix.

4. The traveling wave tube as claimed in claim 1, wherein in said elongated member comprises a dielectric rod having a plurality of elemental conductive flakes disposed over its entire surface in isolated relationship with each other, the length of said conductive flakes as measured along the longitudinal axis of said elongated member being less than the distance between successive turns of said N-filar conductive helix.

5. The traveling wave tube as claimed in claim 1, wherein in said elongated member is disposed helically about said N-filar conductive helix in the same direction and at a greater pitch than the turns of said N-filar helix.

6. The traveling wave tube as claimed in claim 1 wherein in $N=1$ making said N-filar helix a unifilar helix, said wave capable of being propagated by said helix is a forward wave, said helix has a circumference per turn of from 0.2 to 0.9 of a free space wavelength at the frequency of said forward wave, said electron stream is a hollow, cylindrical stream having a diameter of at least 0.6, the inner diameter of said helix, said electron stream is directed concentrically through said helix thereby to cumulatively increase the magnitude of said forward wave as it is propagated along said helix, and said elongated member is adapted to attenuate a predetermined band of frequencies which includes the frequencies at which oscillations in both the low and the high frequency backward wave modes would occur and which does not include the frequency of said forward wave.

7. The traveling wave tube as claimed in claim 1 wherein in said wave capable of being propagated by said helix is a high frequency backward wave, said electron stream is a hollow cylindrical stream having a diameter of at least 0.6 the inner diameter of said helix, said electron stream is directed concentrically through said helix thereby to cumulatively increase the magnitude of said high frequency backward wave as it is propagated along said helix, and said reflectors being adapted to attenuate first and second predetermined bands of frequencies which include, respectively, a first band of frequencies in which oscillations on the low frequency backward wave mode would occur and a portion of a second band of frequencies wherein oscillations on the high frequency backward wave mode would occur, the frequency of said backward wave of increasing magnitude being within the remaining portion of said second band of frequencies.
